United States Patent Office.

ALBERT W. ROBERTS, OF HARTFORD, CONNECTICUT, ASSIGNOR TO P. JEWELL & SONS, OF SAME PLACE.

Letters Patent No. 65,767, dated June 11, 1867.

IMPROVED APPARATUS FOR DRYING HIDES, LEATHER, &c.

The Schedule referred to in these Letters Patent and making part of the same.

TO ALL WHOM IT MAY CONCERN:

Be it known that I, ALBERT W. ROBERTS, of Hartford, county of Hartford, and State of Connecticut, have invented certain new and useful improvements in the process or the employment of Mechanism for Drying Leather, Staple, or other material; and to enable others skilled in the art to make and use the same I will proceed to describe the process or mechanism by which it is produced by referring to the drawings, in which the same letters indicate like parts in each of the figures.

The nature of this invention consists in combining mechanism for receiving and forcing air with air-receiving, circulating, and heating tubes, arranged within a heated chamber, (as a chamber of a steam boiler or other heater, which is constructed expressly for heating or generating steam, &c.,) with a proper receptacle or room for placing hides, leather, staple, or other material, for being dried.

The object of this invention is to use accumulated artificial heat, used for heating, generating steam, &c., for heating air for drying, without any expense for fuel. In the accompanying drawings—

Figure 1 is a front elevation.

Figure 2 is a side elevation.

Figure 3 is a top or plan view.

The boiler and walls, its front, and fire heating apartment are very much like those now in common use. A are air-heating tubes, arranged in the fire-chamber B of a boiler or other heated chamber, (used for purposes other than for drying,) so that the heat of the fire may pass or mingle and circulate among the tubes, and so that the surfaces thereof may be heated without essentially detracting the heat from the boiler, or other purpose for which it was originally provided. C is a fan-blower or its equivalent, such as are in common use, which connects with the induction pipe D. This blower is operated by means of a belt working upon the pulley E in the ordinary way. The speed of this blower (air-pump) or its equivalent, for blast and heat, may be increased or diminished, more or less, according to the amount or change of heat required, according to the varying circumstances of the case. F is an eduction pipe, which conducts the air into the drying-apartment G through the tubes A. This apartment G is provided with grates, racks, shelves, &c., for the convenience of hanging or placing the article in proper position for drying, and is made of any desirable size or shape which will be best adapted for the purpose for which it is used. This apartment G is also provided with openings for the escape or displacement of air when desirable; also to regulate the condition of the air within the apartment. Now, it will be clearly seen that, when the power is applied to the pulley E of the air-pump or blower, or their equivalents, the air will be drawn into the blower, and forced forward therefrom, through the heating tubes and eduction tube, into the drying-apartment G, which may be heated to a greater or less degree by the velocity or pressure of the blower C or its equivalent.

I believe I have thus shown the nature, construction, and mode or process of operation so as to enable others skilled to make and use the same therefrom.

What I claim, therefore, and desire to secure by Letters Patent, is—

Driving the air through heating tubes A, arranged in a heating-chamber, B, into a drying-apartment, G, substantially as and for the purpose described.
